United States Patent Office

Des. 187,274
Patented Feb. 23, 1960

187,274

DESK TELEPHONE COIN BOX

Benjamin W. Friedman, Bridgeport, Conn.

Application July 9, 1959, Serial No. 56,708

Term of patent 14 years

(Cl. D26—14)

Fig. 1

Fig. 2

The dominant features of my new design are shown in solid lines in the drawing.

I claim:

The ornamental design for a desk telephone coin box, as shown, and described.
